OP 15,597

EX

DESIGN.

G. BÖTTICHER.

MOHAIR PLUSH.

No. 15,597.

Patented Dec. 9, 188

UNITED STATES PATENT OFFICE.

GEORG BÖTTICHER, OF WURZEN, SAXONY, GERMANY.

DESIGN FOR MOHAIR PLUSH.

SPECIFICATION forming part of Design No. 15,597, dated December 9, 1884.

Application filed September 17, 1884. Term of patent 3½ years.

To all whom it may concern:

Be it known that I, GEORG BÖTTICHER, of Wurzen, in the Kingdom of Saxony and Empire of Germany, have invented and produced 5 a new and original Design for Mohair Plush, of which the following is a full, clear, and exact description.

Reference is to be had to the accompanying photograph, forming a part of this specification, and which fully illustrates my design.

The leading feature of my design consists of the representation of four dragons arranged around a fanciful center-piece, and having a crown above the heads of the upper pair of 15 dragons. In the pattern each upper dragon serves as a lower dragon for another center-

piece, and each lower dragon serves as an upper dragon for another center-piece. This arrangement brings each crown between two center-pieces laterally, and above the heads 20 of two dragons and below the tails of two other dragons, as fully shown in the photograph.

I claim—

The design for mohair plush herein shown and described, the same consisting of the representation of four dragons arranged around 25 a fanciful center-piece, and having a crown above the heads of the two upper dragons.

GEORG BÖTTICHER. [L. S.]
